UNITED STATES PATENT OFFICE.

ARTHUR R. KRAUSE, OF WOODHAVEN, NEW YORK, ASSIGNOR TO LION ELECTRIC MANUFACTURING CO., INC., A CORPORATION OF NEW YORK.

DESIGN FOR A LIGHTING-FIXTURE LAMP BRACKET OR HOLDER.

Application filed November 23, 1923. Serial No. 7,855. Term of patent 7 years.

To all whom it may concern:

Be it known that I, ARTHUR ROBERT KRAUSE, a citizen of the United States, residing at 3966 Fulton Street, Woodhaven, Long Island, county of Queens, city and State of New York, have invented a new, original, and ornamental Design for a Lighting-Fixture Lamp Bracket or Holder, of which the following is a specification, reference being had to the accompanying drawing, which forms a part of this application and illustrates my design applied to a lighting fixture lamp bracket or holder.

In the drawing, the single figure is a front elevation and is in the nature of a solid of revolution.

I claim:

The ornamental design for a lighting fixture lamp bracket or holder, as shown.

ARTHUR R. KRAUSE.
